UNITED STATES PATENT OFFICE.

CARL R. HERMAN, OF CRAFTON, PENNSYLVANIA, ASSIGNOR TO THE MORRIS AUTOMATIC SCALE COMPANY, OF CRAFTON, PENNSYLVANIA, A CORPORATION OF SOUTH DAKOTA.

ELECTROMAGNETIC DEVICE.

Application filed December 1, 1921. Serial No. 519,079.

To all whom it may concern:

Be it known that I, CARL R. HERMAN, a citizen of the United States, residing at Crafton, in the county of Allegheny and 5 State of Pennsylvania, have invented certain new and useful Improvements in Electromagnetic Devices, of which the following is a specification, reference being had therein to the accompanying drawings.

- 10 This invention relates to automatic cut-off scales and has for an object to provide in combination with a scale mechanism including a fulcrumed beam and sliding cut-off, of means for holding the sliding cut-off in open 15 position to permit the flow of material from a hopper to a receptacle, and of employing fixed magnets the magnetic attraction of which is at times increased by the movement of the scale beam.
- 20 A further object of the invention is to provide, in combination with a scale cut-off, of spaced magnets and electrical means for energizing the same, with a bridge piece actuated by the swaying of the beam to close the 25 magnetic circuit to strengthen the magnetic attraction of the magnets to thereby attract the detent as an armature to release the cut-off.

With these and other objects in view the 30 invention comprises certain novel elements, parts, units, mechanical and electrical constructions, combinations and arrangements, as disclosed in the drawing, together with mechanical and electrical equivalents thereof, 35 as will be hereinafter more fully described and claimed.

In the drawings:

Figure 1 is a view of a fragment of a scale mechanism showing a part of a scale beam 40 and cut-off with the cut-off actuating mechanism associated therewith;

Figure 2 is a top plan view of the magnets and bridge piece, as indicated by line 2—2 of Figure 1;

45 Figure 3 is a fragmentary detail view showing the position of the parts at the instant the magnetic circuit is closed, the detent raised and the switch opened before the detent has fallen;

50 Figure 4 is a diagrammatic view of the magnets and magnetic mechanism;

Figure 5 is a detail perspective view of the cut-off and spring actuating mechanism, and

55 Figure 6 is a detail fragmentary view of

the connection of the bridge piece with the scale beam.

Like characters of reference indicate corresponding parts throughout the several views.

The present invention is adapted to be used with automatic cut-off scales of various types, and the disclosure of a specific type in the drawing is not intended as any limitation upon the present invention. The type 65 as disclosed comprises supports 10 with a frame member 11 carried thereon above which a scale beam 12 of any type is mounted in any usual and ordinary manner, as by means of the upright 13 and bearing 14. 70

Supported upon the frame 11 is a hopper 15 having a discharge chute 16, and movable relative to the hopper 15 and chute 16 is a sliding cut-off 17 having an opening 18 properly proportioned and positioned to register 75 at times with the opening of the chute 16 to permit the flow of material from the hopper 15 through such opening and chute 16 to a receptacle or package supported upon the scale platform, not shown, but connected 80 with the beam in any usual and ordinary manner, as by the rod 19.

The sliding cut-off 17 is connected with a bell crank lever 20 by means of a link 21 and a spring 22 is provided for the purpose of 85 throwing the cut-off from the open position shown at Figure 1 to the closed position shown at Figure 3 when the cut-off is free to move. A hand extension 23 provides means for moving the cut-off to open position 90 against the tension of the spring 22, which tends to move the cut-off to closed position when released by the detent 24. As shown at Figure 1 this detent 24 hooks over the end 95 of the cut-off 17 but it is obvious that it may be arranged to engage the cut-off in any usual and well known manner. This detent 24 is pivoted at 25 and is thereby free to swing between the position shown at Figure 1 and the position shown at Figure 3 and tends to 100 maintain the position shown at Figure 1 by reason of its own weight. The detent 24 carries an armature 26 properly positioned to be attracted by the cores of the magnets 27 and 28. The magnets 27 and 28 are energized in any approved manner, as by the coils shown diagrammatically at Figure 4 from any approved source of supply, as the line wires 29 and battery 30.

105 Mounted convenient to the limit of move- 110

ment of the cut-off 17 is a switch plate 31 electrically connected with the magnets as indicated more particularly at Figure 3 and a switch 32 is provided with an extremity 33 in position to be engaged by the end of the cut-off 17, as shown more particularly at Figure 3 and to be opened when the cut-off has reached the limit of its movement under the stress of the spring 22. The switch 32 is provided with a spring 34 which tends to hold the switch in closed position when free so to act, which occurs when the cut-off has been moved to open position, as shown at Figure 1.

15 It will be noted that the magnets 27 and 28 are separate and normally are not bridged, but a bridge piece 35 is provided carried by a stem 36, which in turn is carried by the beam 12. The manner of carrying this bridge piece by the beam is not essential, but as shown, the spindle 36 is provided with slip action, as indicated at Figure 6, a constriction 37 being provided with a set screw 38 engaging therein which permits 20 the beam to move a limited distance after the bridge 35 has engaged the tops of the cores of the magnets, as shown at Figure 3. This is not essential to the invention and a bridge piece 35 carried rigidly by the beam 25 would serve the purpose, which may be accomplished by manipulating the set screw 38 when desired.

Under normal conditions the magnetic attraction of the magnets 27 and 28 when the 30 bridge piece 35 is not in engagement therewith, is not sufficient to attract the armature 26 to lift the detent 24. When, however, the beam 12 is tilted by the movement of the rod 19 in the direction indicated by the arrow to bring the bridge piece 35 into engagement with the tops of the cores of the magnets 27 and 28, the bridging of such magnets will close the magnetic circuit, whereby the attraction is greatly increased to attract 40 the armature 26 and lift the detent 24, permitting the spring 34 to move the cut-off 17, which, at the limit of its movement, kicks open the switch 32 and de-energizes the magnets 27 and 28. The de-energizing 45 of these magnets makes it feasible to elevate the bridge piece 35 by the action of the beam when the receptacle or other package upon the scale platform has been removed or replaced by an empty one. By this 50 structure any electrical contact controlled by the beam has been eliminated and there is

no electrical connection between the beam and any operating part of the device, the bridge piece 35 only closing the magnetic circuit and not the electric circuit. 60

As soon as the filled receptacle has been replaced by an empty one the cut-off is manually opened, which permits the material to again flow and simultaneously the spring 34 closes the switch but, the bridge piece, 65 having previously been lifted by the release of the scale platform, the magnetic attraction of the magnets 27 and 28 is again insufficient to attract the armature 26 until again bridged by the swaying of the beam. 70

What I claim is:

1. The combination with a scale embodying a fulcrumed beam and a movable commodity cut-off, of a detent adapted to hold the cut-off in delivery position, spaced electromagnets positioned adjacent the detent, means to energize the magnets, a bridge piece carried by the beam adapted to close the magnetic circuit of the magnets to attract the detent, and means actuated by the movement of the released cut-off to de-energize the magnets. 75

2. The combination with a scale embodying a fulcrumed beam, a cut-off and means tending to close the cut-off, of a detent 80 adapted to hold the cut-off in open position against the tendency to close, spaced electromagnets adjacent the detent, an armature carried by the detent positioned to co-operate with the magnets, an electric circuit 85 for energizing the magnets including a switch, a bridge piece carried by the beam proportioned to close the magnetic circuit between the magnets and attract the detent, and means carried by the cut-off to open the 90 switch to de-energize the magnets.

3. The combination with spaced magnetic coils of an electric circuit connected with the coils and adapted to energize the same, an armature proportioned to resist the magnetic attraction of the coils, a bridge piece, and mechanical means for moving the bridge piece to close the magnetic circuit to augment the magnetic force of the coils to overcome the resistance of the armature. 100 105

In testimony whereof I hereunto affix my signature in presence of two witnesses.

CARL R. HERMAN.
